UNITED STATES PATENT OFFICE.

AXEL JOHNSON, OF OAKLAND, CALIFORNIA.

CAN-OPENER.

1,116,592.

Specification of Letters Patent. Patented Nov. 10, 1914.

Application filed June 1, 1912. Serial No. 700,855.

To all whom it may concern:

Be it known that I, AXEL JOHNSON, a citizen of the United States, residing at Oakland, in the county of Alameda and State of California, have invented certain new and useful Improvements in Can-Openers, of which the following is a specification.

Heretofore it has been the practice of inclosing "tamales" in a wrapper of layers of corn husks, that the same could be easily steamed, the corn husk readily removed at the time of serving, and the "tamale" served in a whole unbroken condition.

The practice of inclosing "tamales" in a husk wrapper has proven very unsanitary and a rather difficult operation of removing the layers of husk and still not breaking the "tamale" upon serving, so it is a later and more sanitary practice of canning "tamales" but to the present time there has not been devised a can opener which would quickly open the can, that the "tamale" therein could be taken therefrom in a whole unbroken condition.

The hereinafter described invention relates to an improved can opener for opening cans containing solids or semi-solids, such as "tamales," and has for its principal object to provide an opener adapted to completely sever the head from a can at one operation, to cut the head therefrom close to the securing bead thereof leaving comparatively little metal remaining on the body of the can, to provide an opener of the above character adapted to receive cans of various heights and diameters, and to provide an opener having a seat and guide for the can, so constructed and positioned that when the can to be cut is properly placed thereon the end to be severed will be in proper cutting relation to the cutter.

The invention consists in a supporting base, an arm extending upwardly therefrom and overhanging the same, a can seat supported by said base, a plunger mounted to reciprocate in said arm above said base, a cutting knife secured to the underside of said plunger, a guide at the rear of said can seat for properly positioning the heads of the cans to be opened relative to said cutting knife, and means for operating said plunger to force the knife carried thereby into the can head and sever the same from its body.

With the above mentioned and other objects in view, the invention consists in the

novel construction and combination of parts hereinafter more fully described, illustrated in the accompanying drawings, and pointed out in the claims hereto appended.

Referring to the drawings disclosing a complete constructed device for fully carrying out my invention Figure 1 is a broken side elevation of my improved device in the operation of severing a head from a can, showing in dotted lines the edges of the cutting knife carried by the plunger seated in the can after severing the top therefrom. Fig. 2 is a vertical sectional view of Fig. 1 with the can removed, disclosing the shape of the guide at the rear of the can seat, the manner of detachably securing the can seat and the cutting head to their respective supporting members and the manner of pivotally mounting the operating lever. Fig. 3 is a detail of the cutter head disclosing the knife carried thereby. Fig. 4 is a top plan view of a can disclosing the close even cut made by the cutter head.

Referring to the drawings, the reference numeral 1 designates the base of a suitable casting formed with the supporting base flanges 2 and provided at its rear with an integral upstanding arm 3, the upper end 4 of which is provided with a vertically extending bore 5 and overhangs the base 1, as in Fig. 1. A vertical bore 6 is formed in the base directly below the bore 5 and in which is adapted to be positioned a standard 7, in the upper end of which is formed a screw-threaded bore 8, in which is positioned the screw-threaded stud 9 projecting from the underside of a circular can seat 10. The standard 7 is provided with transversely extending openings 11, adapted to receive a securing pin 12, adapted to extend through aligned openings 13 into the bore 6. Extending upwardly from the rear edges of the can seat 10 is a flange 14 in the form of a semi-circle in plan and the same is provided with an overhanging bead 15 which provides a groove 16 immediately above the seat in which is adapted to be positioned the projecting end bead or seam of a can.

Mounted to reciprocate in the vertically extending bore 5 is a plunger 17, provided at its lower end with a screw-threaded bore 18 in which is detachably secured a screw-threaded stud 19, projecting from the upper side of a circular cutter head 20 which is in turn provided with a downwardly projecting annular flange 21. The recess formed

in the cutter head 20 by the flange 21 provides a seat for a plate 22, detachably secured in place by screws 23 and provided with an annular flange 24 adapted to rest 5 against the inner periphery of the flange 21 and project below the same. The lower edge of the flange 24 is formed with a series of points or serrations 25 upwardly and inwardly beveled as at 26, the whole forming 10 a cutting edge or knife. An operating lever 27 is pivoted as at 28 between suitable ears 29 extending upwardly from the overhanging portion 4 of the casting and is also pivotally mounted as at 30 between ears 31 15 formed at the upper end of the plunger 17, and it will be observed that the lever provides a means for reciprocating the cutter head 20 carrying the knife.

In the operation of my device, a can is 20 seated on the can seat 10 with the bead thereof in the groove 16 which provides a guide for the same, the lever 27 is now moved downwardly forcing the pointed ends 25 of the knife into the top of the can, as in 25 Fig. 1, completely severing the top therefrom, leaving a smooth edge remaining at the severed end of the can.

In cans containing semi-solids, the above 30 operation is performed and the can is turned with the other end up and it is completely severed from the body as was the first, allowing the operator to press the contents from the can as a whole and in an unbroken state by pressure of his thumbs against the 35 last severed end of the can.

By constructing the standard 7 so that it 40 may be adjusted, cans of various heights may be opened by the device and by constructing the standard 7 and the plunger 17 respectively with a removable can seat and cutter head, other can seats and cutter heads of various sizes may be used, adapting the device for opening cans of different diameters.

45 Having thus fully described my invention what I claim as new and desire to protect by Letters Patent is—

1. A can opener, the same comprising a

supporting base, an integral arm extending upwardly therefrom and overhanging the 50 same, a can seat supported by said base and on which a can to be opened is positioned, a plunger mounted to reciprocate in said arm over said seat and coöperate therewith, a circular cutting knife detachably secured to 55 the under side of said plunger, an overhanging guide at the rear end of said can seat for engaging a can bead to retain the can on said seat, when the cutting knife is withdrawn therefrom for severing the head and 60 for properly positioning the can to be opened relative to said cutting knife, and means for operating said plunger to force the knife carried thereby into the can head.

2. In a can opener, the same comprising a 65 supporting base, an integral arm extending upwardly therefrom and overhanging the same, a can seat standard adjustably supported by said base, a circular can seat detachably carried by said standard and on 70 which the can to be opened is positioned, a plunger mounted to reciprocate in said arm over said seat and coöperate therewith, a plunger head detachably secured to the lower end of said plunger, a circular cutting 75 knife secured to the under side of said plunger head, an upwardly extending overhanging guide flange at the rear of said can seat for properly positioning the can to be 80 opened relative to said cutting knife and for receiving the can bead and preventing the upward movement of the can when the knife is withdrawn therefrom after severing the head thereof, and an operating handle fulcrumed to the upper section of said arm and 85 to said plunger for operating said plunger to force the knife carried thereby into the can head to sever the same from its body.

In testimony whereof I have signed my name to this specification in the presence of 90 two subscribing witnesses.

AXEL JOHNSON.
